UNITED STATES PATENT OFFICE.

JESSE H. SROFE, OF KOKOMO, INDIANA, ASSIGNOR OF TWO-THIRDS TO
JOHN E. FREDERICK AND HARRY WARD, OF SAME PLACE.

DESIGN FOR A WIRE FENCE.

SPECIFICATION forming part of Design No. 30,912, dated May 30, 1899.

Application filed May 4, 1899. Serial No. 715,624. Term of patent 14 years.

To all whom it may concern:

Be it known that I, JESSE H. SROFE, a citizen of the United States, residing at Kokomo, in the county of Howard and State of Indiana, 5 have invented and produced a new and useful Design for Wire Fences, of which the following is a specification.

In the drawing I have shown a side elevation of a wire fence presenting my design. 10 As shown in the drawing, the leading or important feature of my design consists in a fence having horizontal or strand wires A, B, C, D, and E running longitudinally through the fence and the double pickets F, having curved 15 tops, which overlap or cross each other above the top of the horizontal or strand wire A and each having inclined portions f, converging toward each other through the space between the strands or wires A and B and the inclined 20 portions f' diverging from each other through

the space between the strands or wires B and C, and the inclined portions f² converging toward each other through the space between the strands or wires C and D, and the inclined portions f³ diverging from each other 25 through the space between the strands or wires D and E, and so on, from the top to the bottom of the fence. A fence constructed of pickets arranged as above described presents the appearance of horizontal strands or wires 30 and diagonally-arranged crossing wires extending from the top to the bottom.

What I regard as new, and desire to secure by Letters Patent, is—
The design for a wire fence herein shown 35 and described.

JESSE H. SROFE.
